PLOW MINING METHOD AND APPARATUS

Featherstone Bainbridge, Fenham, Newcastle-on-Tyne, England, assignor to Huwood Mining Machinery Limited, Gateshead-on-Tyne, England, a company of Great Britain

Application February 10, 1949, Serial No. 75,699

Claims priority, application Great Britain
February 12, 1948

1 Claim. (Cl. 262—8)

1

This invention comprises improvements in and relating to the mining or winning of coal or other material, and is concerned with that method of operation (hereinafter termed method of the kind described), in which the material is obtained by slicing or stripping it from a face by means of a device, herein for convenience termed a plough, which is traversed under power along the face and is provided with a wedge formation and a cutting edge to cut and lever away the material.

This method has heretofore been used in coal mining but the present invention is not restricted to the winning of coal but may be applied to the treatment of mine or like faces of other materials.

Heretofore, the plough has been constructed to slide over the floor and to direct coal on to a chain-scrapers conveyor laid along the face and it has been kept up to the coal face by running it along the floor in contact with the conveyor structure which has been made appropriately heavy or massive for the purpose. It has been hauled along the face by a rope haulage and has been provided with ramp or scoop means which, as the plough was hauled along stripping the face, directed the cut down coal on to the conveyor.

The method referred to above as heretofore applied to coal mining, requires no undercutting of the coal, and no shot firing to break down the coal, and the loading of the coal on to the conveyor has been effected by the plough concurrently with the cutting. It is therefore a simple method and in appropriate circumstances has obvious advantages from the economical and practical standpoints.

The method has been used with success in the mining of soft coal which can be relatively easily sliced or stripped from the face. In the case of comparatively hard coal, however, difficulties arise in getting the plough to slice the coal owing to the resistance which the coal offers to cutting by the plough due to its hardness. Another disadvantage is that it has usually been necessary to cut out stalls at the ends of the coal face to enable the plough to be given a start because it has been required to be held up to the face by the conveyor structure which has only extended to the ends of the face. Moreover, when cutting is finished, the conveyor must be moved to a new position and in the ordinary way the advancing of conveyors in coal mines is a relatively long and tedious procedure.

An object of the invention is to provide improved method and apparatus whereby the above difficulties can be overcome and mining by a method of the kind described, carried out thereby substantially without departing from conventional practice in the lay-out of a mine.

2

According to this invention, a method of the kind described is characterised in that the plough is traversed along the face supported by side structure of a conveyor laid along the face and extended beyond an end of the face into a gate or road and that for the start of a movement along the face, the plough is brought into the gate or road supported by the conveyor side structure and then caused to start its operation by cutting a kerf, for entry of the thin end of the wedge-formation of the plough, round the corner of the said end of the face, after which the plough is caused to continue cutting of a kerf for entry of such wedge-formation as the plough proceeds along the face supported by the side structure of the conveyor.

According to another aspect of this invention, a method of the kind described is characterised in that the plough is mounted to travel along the face supported by side structure of a conveyor into which the plough delivers material won from the face, and the conveyor structure is extended beyond the ends of the face into gates or roads and in the latter is supported on portable structures made capable of ready movement along the gates or roads.

The plough is suitably kept up to the face at the start of and during the run along the face by preventing it from rising from the structure by which it is supported and by preventing it from partaking of lateral movement with respect to that structure.

Another feature of the invention consists in bringing the plough, supported by the conveyor side structure, into one of a pair of gates or roads on reaching the end of the face at the termination of a slicing or stripping operation on the face, and then moving the plough and end parts of the conveyor structure along the gates or roads to advance to a new position while at the same time advancing the conveyor structure between such end parts by means operating on the structure at spaced points along its length.

Apparatus according to the invention comprises a conveyor fitted with side members forming supports for the plough in its movement along the face, such conveyor structure extending at an end thereof into a gate or road at an end of the face so that the plough may substantially wholly enter such gate or road supported by said side members, and cutting means provided at the thin end of the wedge formation of the plough and operative continuously to cut a kerf in the material for entry of the wedge formation.

The plough and the said side members are constructed to have such engagement with each

other that, at the start of and during the operation of slicing or stripping the face, the plough is prevented from rising from the conveyor structure and from partaking of lateral movement with respect to that structure.

For the purpose of advancing the conveyor structure after a stripping operation on the face, portable structures made capable of ready movement along gates or roads are provided to support end parts of the conveyor structure in such gates or roads. The part of the conveyor structure between these end parts can be moved forward at the same time by means of jacks or sylvesters disposed at spaced points along that part of the conveyor structure.

The winning operation is materially assisted by the fact that the invention provides for the formation of a kerf continuously in advance of the thin end of the plough wedge-formation in combination with the mounting of the plough on the conveyor structure and the extension of the latter at the ends into gates or roads thus supporting the plough conveniently for starting and continuing the formation of such kerf. Hard coal faces can be efficiently dealt with because at all the time the plough is moving, including at the start, the continual formation of the kerf facilitates the cutting operation required of the plough and enables the thin end of the wedge-formation easily to enter the material for levering it away. Naturally, the improvements of the invention can be applied to the winning of soft coal or other like materials from faces, and when a cut is finished simple operations suffice to move the whole structure, including the plough, up to a new position, and the lay-out of a mine comprising face and end gates or roads may be according to normal practice, and no formation of stalls is required. The moving up operation is readily effected, for although the conveyor structure is suitably made of heavy calibre for the running thereon of the plough, that part of it lying along the face can be moved up by the jacks or sylvesters disposed at the spaced points along its length, while the portable structures in the gates or roads enable the end parts to be dealt with readily even when the plough is supported on them.

In order to enable the invention to be readily understood, reference is directed, by way of example, to the accompanying drawings in which:

Figure 1 is a plan of coal-mine workings installed with apparatus in accordance with the present improvements and operative for carrying out the method of the invention in connection with the mining of coal.

Figure 2 is a view to a larger scale showing part of the coal face, a sectional plan of the plough and a part, in plan, of a conveyor for taking away the coal removed from the face.

Figure 3 is a rear elevation of parts shown in Figure 2.

Figure 4 is a sectional elevation looking on the right-hand end of Figure 2 and the left-hand end of Figure 3, parts being omitted for the sake of clearness.

Figure 5 is a fragmentary view showing details.

Figure 6 is a plan view of the conveyor troughing and associated parts.

Figure 7 is a sectional view showing apparatus of the invention in a main gate or road.

Figure 8 is a sectional plan of Figure 7.

Figure 9 is a view similar to Figure 7 but taken at a tail gate or road.

Figure 10 is a sectional plan of Figure 9.

Figures 11 and 12 are side elevations of parts of a wheeled structure situated in the main gate.

Figure 13 is a fragmentary elevation of the plough, looking on the right-hand of Figure 2, and

Figure 14 embodies an elevation of a modified construction of plough.

In Figure 1, a coal face 1 is shown in process of being stripped by a so-called plough 2 which is mounted to travel along the conveyor 3 and is able to attack the coal in either direction of such travel. The conveyor is laid along the face 1 and extends at both ends into gates or roads 4, 5.

At the ends the conveyor comprises sections, hereinafter referred to, which are embodied in portable structures 6, 7. The latter are fitted with wheels engaged with tracks 8, 9, so that they may be moved up as the face 1 advances, as indicated by the arrows. The plough 2 is of broadly known form in that it embodies a structure which has wedge-formations, at 10, presented in opposite directions, which are operative to attack the coal face 1 somewhat like the edge end

of a chisel. As will be understood, one wedge-formation of the plough 2 is effective in one direction of travel of the plough along the coal face 1 and the other is effective when the movement of the plough is in the opposite direction.

The coal removed by the plough is loaded thereby after usual manner on to the conveyor 3 which is shown of chain-scraper type though, alternatively, a trough conveyor with belt could be used, laid along the face parallel thereto.

As shown by Figures 2 to 4, the plough comprises a main body or carriage 11 of bridge-like form lying astride the conveyor troughing, and carrying at one side a part 12, hereinafter for convenience termed the wedge part, having the wedge-formations 10. This wedge part 12 overhangs the inner side of the troughing and extends practically to the level of the floor 13 along the face 1 while rising substantially the height of the seam. The wedge-formations 10 are defined by renewable wedging blades 14 which extend curvedly at an incline from the thin ends of the wedge towards the main body 11, see Figure 2. Between the wedging blades 14 and end parts 15 of the main body 11 which slope down to floor level and serve to clean the floor of

remnants of broken down coal, the plough has inclined ramps or scoops 16 which guide the main broken-down coal into the conveyor troughing.

The plough is mounted to travel along the conveyor troughing on four vertical wheels 17 and is prevented from slewing horizontally by four horizontal wheels 18 which take bearing on opposite sides of the troughing. The conveyor is made of relatively heavy construction. As shown in Figures 4 and 5 the side members of its troughing are suitably of Y section built up from Z-section parts 19 placed back to back and secured by bolts 20 to the bottom 21 of the troughing.

The bottom 21 is thus elevated to provide space beneath for the return flight of the conveyor scrapers 22, and so that the chains 23 of these scrapers may bear on the inner flanges of the lower Z-section parts 19. Arranged on the outer sides of the troughing 19, 21 are channel section members 24. These latter have spaced along their length and welded thereto, pairs of lugs 25 which are spigoted to engage holes in

such members, Figure 5. These lugs engage over

the outer flanges of the side members 19 of the conveyor troughing, Figures 2, 4, 5 and 6, and are secured thereto by removable pins 26 passed through holes in the parts 25, 19. It will be realised that the construction of the conveyor and members 24 is such that the parts may be dismantled easily to get at the lower scrapers and chains of the conveyor, should that be necessary at any time. Between the flanges of the members 24, the running wheels 17 of the plough are entered. These wheels are slightly coned to fit between the flanges and there is a pair at each end of the plough carried by parts of, or brackets on, the main body 11 which depend over or overhang the conveyor 3 on the outside. They are carried on horizontal spindles running in suitable bearings and it will be apparent that the upper flanges of the members 24 will prevent the plough 2 from rising on either side and that the plough will not tip over away from the coal face 1 but will be kept up to its work. The horizontal wheels 18 of the plough are carried by lower parts of the main body 11 and bear on the outside of the web of the members 24. It will be realised that these wheels, which in plan are situated at the corners of a truncated isosceles triangle whose apex is on the face side of the conveyor 3, provide a desirable support or restraint for the plough against lateral movement, so that it cannot slew horizontally. Altogether, therefore, the wedge part 12 of the plough is kept substantially true with respect to the face and as will be understood this makes for very efficient initiation of the operation of the plough and its continuance satisfactorily in slicing or stripping the face 1.

For cutting a kerf 27, Figure 2, ahead of the thin end of the wedge formations 10 of the plough, a vertical series of picks or cutters 28, Figures 3 and 4, is provided at each end of the wedge part 12 of the plough. These picks 28 are adapted to move in a circular path and for this purpose the sets of picks are mounted on carrier 29 which is a sort of H-shaped structure and has the picks disposed down the sides of the H on the outside edge, see Figure 3. This carrier 29 is holed at two places (as at 39, Figure 2), on the cross-bar part of the H and spans across the outer ends of the two wedging blades 14 of the wedge formations 10 of the plough 2. It may contact slidably with these ends of the blades 14, which are chamfered to provide flat surfaces 31 parallel with the coal face, see Figures 2 and 3. The holes 30 of the carrier 29 are fitted with bearing bushes 32 by which the structure is mounted on roller bearings 33 on a pair of eccentrics 34 carried on roller-bearings 35 on short horizontal fixed spindles 36. Only one of the eccentrics and associated parts is shown in Figure 2 but it is believed that this will be sufficient for a proper understanding thereof. As will be seen from Figure 2, the cross-bar of the H-shaped carrier 29 is set back from the plane of the sides of the H to accommodate it in the outer compartment 37, of a doubly compartmented gear box which is supported on or embodied in the wedge part 12 of the plough and extends along between the wedging blades 14. The spindles 36 are mounted in the walls of this gear box and concentric hub parts 38 of the eccentrics 34 thereon carry gear wheels 39, see also Figure 3. These mesh with a central gear wheel 40 that is driven by a pinion 41 on a drive shaft (not shown) which extends into the inner compartment 42 of the aforesaid gear box and carries therein a gear wheel 43. The latter is meshed 75

with gear wheels 44 mounted on the shafts of a pair of hydraulic or other motors 45 which extend over the conveyor 3 and form part of the main bridge-like structure 11 of the plough 2. It will now be apparent that under the action of the drive from the motors 45, the eccentrics 34 will cause the picks 28 to have quickly repeated movement arising from the motion of the carrier 29 which will receive forward and backward movements with intervening upward and downward movement from the eccentrics. The sets of picks will suitably be withdrawn to the outer edge of the wedging blades 14 on the retractive or backward movement and be projected forward with a rotary motion from that edge to effect a cutting action on the downward movement component. Thus, each set of picks forms a vertical kerf in advance of the adjacent wedging blade 14, the kerf being constantly maintained and formed so that, after each fresh cut when the picks are retracted, the outer end of the corresponding wedging blade 14 can nose itself into the kerf and exert leverage to break away the coal. Of course, it is only the forward set of picks 28 which is effective at any one time. On traverse of the plough in one direction one set of picks is operative, while in the opposite direction of traverse, the other set is effective for kerf cutting. Thus, in Figure 2, the set of picks on the left is operative to cut the kerf 27, the plough being traversed in the direction shown by the arrow. In Figure 3 the same set of picks appears retracted. The depth of the layer of coal removed by the plough may usefully be 12 inches in hard coal, though obviously the depth may be varied according to circumstances. If desired, the sets of picks 28 could be arranged on vertical rods or bars mounted at their ends on revoluble crank discs or devices. Moreover, instead of using the sets of picks for making the kerf, cutter chains or circular saws could be used, though the pick arrangement described, which in its operation simulates a miner's pick action, is to be preferred.

Any suitable power means may be adopted for effecting travel of the plough along the conveyor troughing, and in the drawing haulage by an endless rope 46 is shown and will be hereinafter described.

The conveyor troughing 19, 21 is of sectional form after normal mining practice as will be understood from the portion thereof depicted in Figure 6. The tracks 24, for the plough wheels 17, 18 are also sectional as shown in Figure 6. At the joints between the troughing and track sections 19, 24 cross-members 76 may be laid on the floor for supporting purposes. From the illustration shown in Figures 7 to 12 it will be seen that the end sections, at 47 and 48, of the conveyor troughing and plough tracks extend into the main and tail gates 4, 5 respectively and are supported there by the wheeled structures 6 and 7 aforesaid. The latter support or comprise drive and return heads of the conveyor and the conveyor chains 23 (or belt if used), are looped here to move on their return journey. The wheeled structure 6 (Figures 7 and 8) comprises two parts, shown also in side elevation respectively in Figures 11 and 12, which are joined by the end section 47 of the conveyor-troughing and plough tracks. The one of such parts, that shown in Figure 11, embodies the drive head for the conveyor while the other (shown in Figure 12), comprises a haulage drive. The drive head comprises the motors 49 which operate through fluid couplings 50, reduction gear boxes 51 and

sprocket and chain gear 52 to rotate the drive sprockets 53 of the conveyor chains 23. The haulage drive comprises a drum 54 (about which the endless haulage rope 46 has two or three turns), and a motor 55 which drives the drum 54 through V-belt gearing 56 and a gear box 57. The haulage rope passes to and from the drum 54 over idlers 58 and runs along the top of the conveyor troughing to the wheeled structure 7 in the tail gate 5. In the main gate 4 the wheeled structure 6 spans a gate conveyor 59 on to which coal is shot from the face conveyor down a chute 60 supported on the conveyor drive head. At the wheeled structure 7 in the tail gate 5, the rope 46 passes over the vertical grooved pulleys 61, Figures 9 and 10, and then moves in a loop over the horizontal grooved pulley 62. The tension on the rope is adjustable here by adjustment of the frame 63 containing the pulley 62 and there is also a screw adjustment 64 for the return sprockets 65 of the conveyor chains 23. The structure 7 thus embodies what is generally termed a tension head for the conveyor 3. Means, not shown, may be embodied in the undercarriage parts of the wheeled structures 6 and 7 for adjusting the height of the undercarriage chassis on its wheels in order to accommodate slight variations in the depth of the floor of the gates 4 and 5 with respect to the floor 13 along the face 1.

The wheeled structures 6 and 7 can readily be moved along the gates on the tracks 8, 9 by means of such devices as rotary sylvesters and hauling ropes (not shown). They can thus be relatively easily moved up as the face 1 is advanced. At spaced points along the face conveyor, for example at positions such as are indicated in Figure 1 by the dot-and-dash lines 66, men with sylvesters or jacks at the same time operate on the intermediate part of the conveyor 3 to move that up as well. The whole operation can be performed in a very short time and with much economy of labour as will be understood. The gates are of normal construction and at the end of a run the plough is brought on to the wheeled structure in one of them to be moved up on that structure.

In order to connect the plough to the endless haulage rope 4, use is suitably made of the clamp device shown in Figures 2, 3 and 13. This device comprises two tongs-like parts 67, 68, of which the part 67 is of box-like form mounted across one end of the plough 2. The other part 68, of U-section, is pivotally mounted within the part 67 at 69. The parts 67, 68 have respective grip jaws 70, 71 fitted with slippers 72 to grip the rope 46 on the flight thereof nearest the coal face 1. A heavy grip is necessary to take the strain put on the plough in slicing the face and for this reason the clamp parts 67, 68 are of relatively heavy construction and operated by a hydraulic jack 73 which in turn is operated by an oscillatable hand lever 74. The clamp device is disposed at the rear end of the plough and its position can be changed to the other end thereof according to whether the installation is operating on a left-hand or on a right-hand, coal face. The rope 46 is passed through a hole 75 at one end or the other of the plough structure so as to be beneath and avoid obstruction of the scoops or ramps 16 up which the coal passes to the conveyor 3.

In the operation of the apparatus described, the plough may at the start of a face operation be on the wheeled structure 7 in the tail gate 4, its position being indicated by the dot-and-dash

lines at A in Figure 10. The conveyor 3 would have been moved up or laid along the face and it would be disposed so that the picks 28 at the operative end of the plough are round the corner, at c, of the adjacent end of the face as indicated at the position A. The depth to which the picks are around the corner of the coal face, corresponds to the depth of the layer of coal to be stripped from the face as will be understood. The haulage rope 46 having now been put into operation, the motors 45 of the plough picks 28 are started and the clamp device 67, 68 closed on to the haulage rope. The plough now starts its journey along the face and the full line showing thereof in Figure 10 indicates that the plough has gone just a short distance, a slightly longer distance having been covered in the diagrammatic Figure 1. At the outset, the said picks 28 first start to cut a kerf for the entry of the corresponding wedge formation 18 and thereafter the kerf cutting is continued, as at 27, Figures 2 and 10, for continued entry of the wedge formation and breaking away of the coal. Broken down coal falls in front of the plough and as indicated in Figure 10, and similarly in Figure 1, moves up the corresponding ramp or scoop 16 of the plough into the conveyor troughing 19, 21. In this it is moved along by the scrapers 22 (or belt) to the chute 60, at the head end of the conveyor 3, and from there is deposited on to the main-gate conveyor 59, Figures 7 and 8. As the plough travels along, its weight and lateral forces thereon are exerted through the wheels 17, 18, on the channel members 24 which are secured by the lugs 25 and pins 26 to the outer flanges of the members 19 forming the sides of the conveyor troughing. The said flanges, through the lugs and pins, support the plough tracks 24 and though the outer track members may, as shown in Figures 4 and 6, bear on the floor cross-members 76 disposed at the joints in the side members of the conveyor-troughing, the bulk of the weight, and the lateral stresses, on the plough are taken by the conveyor troughing as will be understood. The plough track members 24 lend weight to the conveyor structure, which is already of relatively heavy construction as aforesaid, and thus assist it in keeping the plough up to the coal face. When the plough 2 completes its cut (dot-and-dash line position a in Figures 7 and 8), the clamp device 67, 68 is released and the haulage motor 55 stopped. The plough is now on the wheeled structure 6 in the mother gate and situated substantially wholly in that gate. By operation of the rotary sylvesters and of the sylvesters or jacks at 66, both aforesaid, the wheeled structures 6, 7 and the conveyor 3 are now advanced to take up position for a return cut on the coal face, as indicated by the dot-and-dash lines at b in Figure 8. Similar kerf cutting and breaking down of the coal to those above described, but by operation of the other set of picks 28 and the corresponding wedge formation 10 are now effected during traverse of the plough 2 along the face to the tail gate 5. For this operation, the direction of movement of the haulage rope 46 is reversed. As the plough travels along, the broken down coal moves up the other scoop or ramp 16 on to the conveyor 3 and it is taken away by the conveyor through the arch formed by the bridge-like main structure 11 of the plough. When the plough reaches the wheeled structure in the gate 5, it will have the position indicated at B in Figure 10. The clamp device 67, 68 is now released, and the haulage motor 55 stopped, whereupon the parts are

again advanced for a fresh operation on the coal face in the opposite direction. The initial position of the plough for this operation is as shown by the dot-and-dash line at C in Figure 10.

Further operation will be understood without more description.

It will be apparent that the bridge-like main body 11 of the plough 2 as illustrated by Figure 4, extends from side to side over the conveyor at a good height. This form of the plough is intended for use on a normal coal seam, say 3' 6" (about 1 metre) high which is relatively high compared with some seams. At the height stated the bridging part of the plough is sufficiently high above the conveyor 3 to enable the cut coal, brought into the conveyor troughing by plough ramp or scoop 16, to pass beneath the bridge to delivery from the conveyor at the main gate 4, when the plough is operating during travel from the main gate 4 to the tail gate 5. Thus, the plough can be operative in both directions of traverse thereof along the face. In one direction, of course, i. e. with the plough moving unidirectionally with the conveyor scrapers or belt, the coal does not need to pass the bridge but when stripping the face by moving the plough in the opposite direction the coal scooped on to the conveyor must pass the plough and it does so through the bridge-form main body or carriage 11.

In a modified example for use with low seams, the conveyor construction and the mounting of the plough 2 on the conveyor may be similar to those above described, as shown in Figure 14. The bridge-form main body or carriage 11 of the plough, however, is of flatter construction with the motors 45 for driving the kerf cutting picks 28 in a lower position. In this example, the bridge cannot be high enough for the coal to pass through it and therefore the plough is made operative to strip coal from the face in one direction of traverse only of the plough along the face, being flitted back to the starting point for a fresh cut. If desired, therefore, a form of plough may be used which comprises only a single wedge-formation and set of picks 28 for stripping the face 1 and a single ramp or scoop 16 for directing the coal on to the conveyor 3. Nevertheless, similar principles of operation are involved to those in the case first described though appropriate modification of the driving means between the motors 45 and the picks 28 would be necessary, as will be understood.

According to a further modification and in order to provide for operations of the plough in higher seams, the carrier 29 of the picks 28 may be extended upwardly as shown by way of example by the dot-and-dash lines at 100 in Figure 3. This provision can be carried out by fitting additional pick-carrying parts to the carrier or by making the side parts of the H-shaped carrier structure detachable and replacing them by pick-carrying parts but of extended height. Similarly, for lower seam ploughs (cf. Figure 14), detachable pick parts of this nature may be fitted.

It is an advantage of the invention that the plough can be adapted to cut practically the full height of the seam because it provides for a clear cut of the face from top to bottom.

The invention employs certain features of the inventions forming subject-matters of my concurrent patent applications Serial Nos. 75,697 and 75,698, but no claim is made herein to these features per se. Obviously, the apparatus described may be provided with features, other than those already referred to, to be found described in the

specifications accompanying such patent applications.

I claim:

Apparatus for stripping material from a face underground, comprising a plough and a conveyor on which said plough is supported during movement thereof along said face, said conveyor being laid along in front of said face and extending at each end thereof into a gate or road at the adjacent end of said face so that the plough may substantially wholly enter the respective gate or road supported by said conveyor, and said plough having a wedge formation at each end so as to be operative on the face in each direction of travel of the plough along the face and the thinner end of each wedge formation lying substantially parallel to said face in the top to bottom direction thereof, said plough and conveyor being engaged with each other on both sides of the conveyor by means operative substantially rigidly to prevent the plough from rising from both said sides of and from slewing laterally with respect to said conveyor, said plough also comprising a series of tools located adjacent and substantially parallel to the tip of said thinner end of each wedge formation, and which are movable back and forth intermittently by quickly repeated movements and operative to pick at said material at numerous points disposed relatively closely together in an approximately straight line to form a kerf of substantially even depth ahead of said tip starting round the corner of said end of said face and of such nature as to be substantially wholly parallel to said face in longitudinal and transverse section, each wedge formation and the respective series of picking tools being so relatively disposed that the thinner end of the wedge formation enters the kerf when the latter is only of shallow depth and this relation between them is maintained throughout the travel of the plough along said face, the conveyor being operative constantly in one direction of travel and the plough being constructed to bridge the conveyor transversely at a high elevation above it sufficient for large lumps of the material fed onto the conveyor by the plough to pass beneath the bridge, and the conveyor at each end being free of the upstanding wall on the far side of the gate or road at each end of the face.
